UNITED STATES PATENT OFFICE.

GEORGE TURNER AND EMILE AUGUSTE FOURNEAUX, OF MANCHESTER, ENGLAND.

AGING MACHINE.

1,403,990.

Specification of Letters Patent. Patented Jan. 17, 1922.

Application filed January 19, 1920. Serial No. 352,511.

To all whom it may concern:

Be it known that we, GEORGE TURNER and EMILE AUGUSTE FOURNEAUX, both subjects of the King of Great Britain, residing at

5 St. James's Buildings, Oxford Street, Manchester, in the county of Lancaster, England, have invented new and useful Improvements in and Connected with Aging Machines, of which the following is a specification.

This invention relates to improvements in and connected with machines known to the piece dyeing and to the calico printing industries as agers, aniline agers, or steamers, and may be applied to any closed or partially closed machine, vessel, or chamber whence it is required to extract certain gases, vapours, or steam from between folds, laps or layers of fabric under treatment therein.

20 Aging machines are mainly of two types. In the one type used almost exclusively for the development of the so-called oxidation aniline black the aging chamber is filled mainly with air; in the other, used largely 25 for the purpose of developing the so-called prussiate aniline black but also for many other purposes, the chamber is filled mainly with steam, though air may be present. In the course of many of the operations commonly conducted in these machines noxious 30 gases are given off which may hinder the proper development of the colour or otherwise interfere with the operation. This is more particularly the case in the aging of 35 aniline blacks, where it is known that the gases given off tend to prevent the formation of ungreenable black and that they may cause tendering of the fibre and soiling of the white parts of the fabric by the deposition 40 of oxidation products of aniline thereon. In such cases it is necessary that these gases should be removed by suitable ventilation.

In both types of aging machines the usual 45 method of ventilating consists in providing one or more openings, generally on top or at the back of the machine, and connecting these openings with a trunk or shaft leading to the open air, the speed of the gases being 50 accelerated in some cases by suitable means such as a steam ejector, centrifugal fan or other device.

This method of ventilation is by no means 55 efficient as the steam or air, vapour and gases appear to be drawn mainly from the space between the edges of the fabric and the walls

of the ager while the steam or air, vapour and gases between the folds or laps of fabric, being in a partial cul-de-sac, are less completely removed. The removal of the 60 noxious gases is thus incomplete.

The object of our invention is to overcome this draw-back and effect a material improvement in the ventilation by providing suction elements between the folds or laps 65 of fabric and applying suction by any known means so as to remove the bulk of the vapours or gases as and when they are generated.

In their simplest form the suction elements 70 consist of an exhaust fan, ejector or equivalent in conjunction with a pipe closed at one end and provided with suitable openings, e. g. a slot, perforations, etc., but it is obvious that the shape, material and general 75 arrangement of the suction elements may be modified to a considerable extent without in any way departing from the fundamental principle of our invention.

As a specific example of the manner in 80 which we propose to carry our invention into practice we describe with reference to the accompanying sheets of drawings one form of suction element which has been found particularly suitable for use in connection with the ordinary type of steam aniline ager, but it must be distinctly understood that we do not mean to restrict ourselves to that particular form of suction element or to any particular method of fitting it or to any one means of applying suc- 85 tion. 90

In the drawings, Fig. 1 is a longitudinal sectional elevation and Fig. 2 a transverse vertical section of the suction element. Fig. 95 3 is an elevation (partly sectional) and Fig. 4 a plan of an ager with the suction element applied and Fig. 5 is a sectional detail of part of Fig. 3 but on a larger scale.

The form of suction element (illustrated 100 by Figs. 1 and 2) consists of what may be termed a double pipe. The lower or heating pipe *a* is heated by steam supplied through a pipe *b* and for the purpose of preventing condensation and drops on the fabric the 105 heat is transmitted to the upper or suction pipe *c* by means of a connecting metal web or plate *d*. The lower pipe *a* is provided with an outlet pipe *a'* connected say to a steam trap to allow the water of condensation to escape. The upper or suction pipe *c* is closed at one end and perforated by 110

drilled holes *c'* at the highest point of its circumference. The suction elements are fitted to the ager in any requisite number and at any required height, but for constructional purposes preferably at two levels as indicated in Figs. 3 and 5 and in such manner that they will eventually lie between the folds or laps of the fabric *e* arranged alternately left and right hand so as to cause fairly equitable division of suction and heat. The fabric *e* enters the ager through the usual sealed mouth *g* and passes over and under guide rollers *h* finally leaving through the sealed mouth *g* in the ordinary manner. The open ends of the upper or suction pipes *c* are connected with other suction pipes *i* and these merge in turn into an ultimate suction pipe *j* at the back of the ager, which pipe is coupled to the suction apparatus, which may be of any suitable type as for example a Ledward's ejector condenser. The degree of suction applied is controlled by a valve not shown but fitted between the ultimate suction pipe *j* and the suction apparatus of whatever kind, and the steam

supply to the ager *f* should be regulated in such manner as to maintain substantially atmospheric pressure within the body of the ager. Once the amount of suction required in any particular ager has been ascertained the controls can of course be made automatic.

What we claim as our invention and desire to secure by Letters Patent is:—

In an apparatus for ventilating aging machines, the combination of a suction apparatus and a double pipe, said double pipe having one pipe perforated and connected to a suction apparatus, the other pipe adapted to be connected to a source of steam and a metal web joining the pipes whereby heat may be transmitted from the last named pipe to the other.

In testimony whereof we have signed our names to this specification.

GEORGE TURNER.

EMILE AUGUSTE FOURNEAUX.
